Primary Examiner — Christy Nemeth(74) *Attorney, Agent, or Firm* — Adsero IP(57) **CLAIM**

The ornamental design for a track for electrical socket, as shown and described.

DESCRIPTION

FIG. 1 is a rear elevation view of a track for electrical socket showing our new design;

FIG. 2 is a top plan view thereof;

FIG. 3 is a front elevation view thereof;

FIG. 4 is a bottom plan view thereof;

FIG. 5 is a left side elevation view thereof;

FIG. 6 is a right side elevation view thereof;

FIG. 7 is a top and back perspective view thereof; and,

FIG. 8 is a top and front perspective view thereof.

The broken lines in the figures are for the purpose of illustrating portions of the track for electrical socket that form no part of the claimed design.
